Primary Examiner — Darlington Ly(74) *Attorney, Agent, or Firm* — Reising Ethington P.C.(57) **CLAIM**

The ornamental design for a vehicle front bumper, as shown and described.

DESCRIPTION

FIG. 1 is a perspective view of the vehicle front bumper; FIG. 2 is a front view thereof;

FIG. 3 is a left side view thereof, of which the right side elevation view is a mirror image; and,

FIG. 4 is a top plan view thereof.

The broken lines in the drawings illustrate portions of the vehicle front bumper that form no part of the claimed design.
